US00D964170S

(12) **United States Design Patent** (10) **Patent No.:** **US D964,170 S**
(45) **Date of Patent:** **** Sep. 20, 2022**

(54) **PACKAGING ELEMENT**

- (71) Applicant: **RATIONAL PACKAGING LLC**, Springfield, TN (US)
- (72) Inventor: **Samuel C. Voorhees**, Louisville, KY (US)
- (73) Assignee: **Rational Packaging LLC**, Springfield, TN (US)
- (**) Term: **15 Years**
- (21) Appl. No.: **29/766,945**
- (22) Filed: **Jan. 26, 2021**

Related U.S. Application Data

- (63) Continuation-in-part of application No. 29/667,167, filed on Oct. 18, 2018, now Pat. No. Des. 908,005, which is a continuation-in-part of application No. 29/593,147, filed on Feb. 6, 2017, now Pat. No. Des. 871,908, and a continuation-in-part of application No. 29/593,144, filed on Feb. 6, 2017, now Pat. No. Des. 871,213.

(57) **CLAIM**

The ornamental design for a packaging element, as shown and described.

DESCRIPTION

FIG. 1 is a top view of a packaging element, showing my new design;

FIG. 2 is a bottom view thereof;

FIG. 3 is a front view thereof;

FIG. 4 is a rear view thereof;

FIG. 5 is a right view thereof; and,

FIG. 6 is a left view thereof.

The symbolic break shown in FIGS. 3-6 indicates that any portion of the article between the break lines forms no part of the claim.

1 Claim, 3 Drawing Sheets
